UNITED STATES PATENT OFFICE.

WILFORD C. TOLES, OF CHICAGO, ILLINOIS.

BENCH-VISE.

SPECIFICATION forming part of Letters Patent No. 613,535, dated November 1, 1898.

Application filed December 3, 1896. Renewed October 7, 1898. Serial No. 692,904. (No model.)

To all whom it may concern:

Be it known that I, WILFORD C. TOLES, of Chicago, in the county of Cook and State of Illinois, have invented certain new and useful 5 Improvements in Bench-Vises, of which the following is a full and clear description, reference being had to the accompanying drawings, in which—

Figure 1 is a plan view. Fig. 2 is a sectional elevation on the line 2 2 of Fig. 1. Fig. 3 is an enlarged vertical cross-section. Fig. 4 is a plan view showing the mutilated nut in detail with the cap G removed, and Fig. 5 is a perspective view of the bench-stop.

15 My invention pertains to that class of bench-vises known as "rapid-acting" vises, and more particularly to the kind shown, described, and claimed in the patent granted to myself and W. H. Toles on the 30th day of October, 1894, 20 and bearing the number 528,190; and it consists in certain improvements and additions to the tool shown in the above-mentioned patent, as will be hereinafter explained.

In the drawings, A is the bed-piece, secured 25 to the bench or work-table by set-screws a and a' from beneath the bench and screws a^2 and a^3 from the side. The bed-piece has a vertical flange A', which forms the stationary jaw 30 of the vise, adapted to be set into the bench so that its face is flush with the front edge of the bench and has conveniently near the center of its width an inward projection A², that should be set snugly into an indentation in the bench. These means for securing the bed- 35 piece to the bench render it permanently immovable therefrom, the inward projection being calculated to resist the strains put upon it and its various fastenings while in service.

40 Downwardly-projecting lugs a^4 a^4 a^4 a^4 on the bed-piece A afford supports in which the parallel bars B and B' may slide. These bars are secured to and form the support for the moving jaw C, which has bosses c and c' , into 45 which the ends of the bars are secured by being turned down so as to present a shoulder, against which the said jaw C is held by nuts b and b' , screwed into the ends of the said bars. The inner ends are connected by a yoke b^2 , 50 so that their parallelism may be preserved. The screw D is rotatably mounted in the moving jaw C and in the yoke b^2 and has the

handle E secured to its outer end. The screw D has a groove cut along the entire length of the thread D of a convenient width, which 55 groove forms a mutilation of each convolution of the threads. A nut-segment F lies loosely in a recess f in the bed-piece and is adapted to be engaged by the threads of the screw D.

60 The handle E has a projection e as one part therewith, and on the boss c^2 of the jaw C is another projection c^3 , against which the projection e strikes. The projection c^3 is continued in the form of a rib extending to the 65 top of the jaw C, forming a tie-piece between the jaw and boss c^2 and serving to stiffen the jaw C to resist the natural strains put upon it. When the handle E strikes with its projection e the projection c^3 , the groove d in 70 the screw D is opposite the nut-segment F, so that the jaw C may be slid to or from the stationary vise, as may be desired, or until the jaws approximate the width of the part to be held. The screw is then turned into 75 engagement with the segment-nut to securely grip the part to be held. In order that the engagement of the screw and the segment-nut may be possible no matter what the relative positions of the two parts may be in regard to the threads, the nut is adapted to move circumferentially and longitudinally, as will be explained. Its outer edge is beveled, as at f' , and the recess has a correspondingly-beveled wall f^2 , against which the beveled end of the nut is forced by the spring f^3 80 between it and the inner wall f^4 of the recess f . The spring is preferably a coiled spring, within which a button-headed pin f^5 lies, its head resting against the wall f^4 . The spring 85 and pin lie partially inclosed in a hole formed in the nut F, as shown in Fig. 2. At the operation of clamping the threads of the screw will be seldom opposite the spaces between the threads on the nut. The rotary movement of the said screw will tend to rotate the segment-nut and the beveled end of the said nut working against the beveled wall of the recess, which rotary movement will result in a longitudinal movement of the nut until it 90 is in the position to be engaged by the screw. The nut is then forced outwardly against the beveled wall and the jaws and by a slight additional movement of the screw will clamp 95 100

the part. The spring is for the purpose of keeping the nut in its outward position.

A casing G serves to protect the nut and its parts from dirt and has a raised edge g , that forms a stop for and determines the circumferential position of the nut relative to the screw in order that when the projections e and e' are in contact the movable jaw may be slid. I further utilize the inward projection on the stationary jaw by inserting in a hole formed in it a bench-stop H, which is in the place where it is needed and is also out of the way of the workman when not required. The stop has a spring N to raise it in order that it may be gripped by the hand when set free by the loosening of the set-screw N'. The face of the stop may be reticulated, as shown.

What I claim as my invention, and desire to secure by Letters Patent, is—

1. In a bench-vise, the combination with the bed-piece having the stationary jaw ris-

ing therefrom, the said jaw adapted to be recessed into the bench and secured thereto, a projection on said stationary jaw adapted to take the strain off the securing-bolts of said bed-piece, and a bench-stop adapted to be supported in said projection, substantially as described.

2. In a bench-vise, the combination with the stationary jaw adapted to be let into the face of the bench, an inward projection on said jaw adapted to take the strains off the securements of said jaw, and a bench-stop supported in said projection, substantially as described.

3. The combination of the jaw A', the inward projection A², and the bench-stop H, having the set-screw N' and the spring N, substantially as described.

WILFORD C. TOLES.
